COIN VENDING MACHINE

Albert E. Skovbo, Portland, Oreg.

Application August 19, 1946, Serial No. 691,474

1 Claim. (Cl. 133—5)

1

This invention relates generally to the handling of money and particularly to a coin vending machine.

The main object of this invention is to produce a machine whereby coins may be vended or change given in exchange for coins of a larger denomination.

The second object is to produce a machine of the class described which will be easy to manufacture and maintain and positive in its operation.

The third object is to construct a machine in the class described in a manner which lends itself to inexpensive manufacture and in which is provided an improved ejector mechanism.

The fourth object is to provide a means for preventing the payment of any coins unless there are enough coins in the stack to make a complete payment.

I accomplish these and other objects in a manner set forth in the following specification as illustrated in the accompanying drawing, in which

Fig. 1 is a perspective view of the complete machine.

Fig. 2 is a vertical section taken along the line 2—2 in Fig. 3.

Fig. 3 is a horizontal section taken along the line 3—3 in Fig. 2.

Fig. 4 is a fragmentary horizontal section of the ejector mechanism showing the position of rest.

Fig. 5 is a view similar to Fig. 4 but showing a group of coins being ejected.

Fig. 6 is a fragmentary vertical section taken along the line 6—6 in Fig. 4.

Fig. 7 is a fragmentary vertical section taken along the line 7—7 in Fig. 4.

Fig. 8 is a view similar to Fig. 7 but showing the position of the parts with the coins partially ejected.

Similar numbers refer to the same or similar parts throughout the several views.

Referring in detail to the drawing, there is shown a base 10 having a ledge 11 formed around the upper edge 12 thereof.

Disposed along the top edge 15 of the base 10 is a floor plate 16 whose down turned edge 17 is under the coin discharge corner 18. Floor plate 16 is cut away along the edge 19, over which are ejected a group of coins 20.

On the floor plate 16 are also mounted the arcuate side walls 21 and 22 whose curved surfaces 23 and 24 conform to the shape and size of the coins 20. The edges 25 and 26 of the members 21 and 22 are parallel and spaced to permit

the coins 20 to pass between them and fall through the opening 19. The members 21 and 22 are spaced to permit the entrance of the arcuate ejector 29 whose up turned end 30 almost equals in height the stack of coins ejected at one operation.

The ejector 29 has a straight portion 31 which stops against the straight face 32 of the member 22. The ejector 29 is mounted on the pivot 33 while the end 34 is provided with a pin 35 on which is mounted the lever 36 on one end of which is disposed the gate 37 which normally prevents the escape of coins 20 as shown in Fig.

4. On the lever 36 is formed a tubular end 38 into which projects the ball 39 formed on the lower end 40 of the bell crank lever, while the pivot 42 is supported by the standards 43. A spring 44 is mounted on the bushing 45 which spaces the bell crank lever 41 between the standards 43. One end of the spring 44 engages the under side of the line 41 to urge it upward while the other end of spring 44 engages the stud 46 which is mounted on the floor plate 16. Spaced from the floor plate 16 is a plate 47, between which and the floor plate 16, the ejector 29 can freely pass, at a level between the top and the bottom of the fifth coin 20—c.

The under side 48 of the plate 47 is above the top of the fifth coin 20—c. The plate 47 is provided with an aperture 49, above which and registering therewith, is a tube 50 forming the holder for the coins whose upper end 51 is flared out somewhat as shown to receive the funnel-shaped opening 52 of the top 53 disposed by the upper end of the casing 54 which extends downwardly to the ledge 11. The casing 54 is provided with a pair of slots 55 which receive the outwardly projecting levers 41 on which are formed the key 56.

It can be seen that if a quantity of coins are placed in the tubes 50 and the parts are in the position shown in Figs. 4 and 6, that is with the coins 20 resting on the floor plate 16, that the depression of a key 56 will actuate the lever 41 and move the ejector 29 to the position shown in Fig. 5 causing the group of coins to be moved, as shown in Fig. 8, out past the edge 19 into the chute 13. As illustrated, the depression of one key 56 will eject five nickels and the depression of both keys 56 eject ten nickels.

In order to prevent a short change operation which might occur if there were less than five nickels within the tube 50, I find it desirable to provide a slug 57 which is placed on the top of the

tube 50 so that when any group of coins descend upon the floor plate 16 the machine cannot be operated at least at the key where the stack of nickels is short.

I am aware that numerous vending and dispensing machines have been constructed in the past. It is, therefore, not my intention to cover such devices broadly, but I do intend to cover all such forms and modifications thereof as fall fairly within the attempted claim.

I claim:

A mechanism of the class described consisting of a straight ejector lever having a pivot point between the ends thereof and having an arcuate ejector at one end whose center of curvature is 15 the pivot point thereof, and having a gate lever pivotly mounted between its ends to the end of said ejector lever opposite its ejector in a manner that one end of the gate lever is juxtaposed to the free end of the ejector, a spring urged actuating 20 lever connected to the other end of said gate lever for simultaneously rocking said ejector lever on its pivot center, and translating said gate lever,

a floor plate supporting said ejector having a coin tube disposed to position coins in the path of movement of said ejector and spaced from said floor plate, side walls under said coin tube having an opening between same for the ejection of coins said one end of the gate lever normally closing said opening, and an opposite opening for the passage of the ejector, said floor plate being cut away outside of the portion which supports the coins, the end of said gate lever in the path of said coins constituting means for preventing the escape of coins from between said walls when no ejection is being made.

ALBERT E. SKOVBO.
